UNITED STATES PATENT OFFICE.

NICOLAUS AUGUST OTTO, OF COLOGNE, PRUSSIA, ASSIGNOR TO THE GAS-MOTOREN-FABRIK-DEUTZ, OF DEUTZ, GERMANY.

IGNITING APPARATUS FOR GAS OR OIL MOTOR ENGINES.

SPECIFICATION forming part of Letters Patent No. 424,345, dated March 25, 1890.

Application filed December 19, 1889. Serial No. 334,292. (No model.) Patented in Italy December 17, 1889, LII, 180, and in England November 22, 1889, No. 18,746.

To all whom it may concern:

Be it known that I, NICOLAUS AUGUST OTTO, a citizen of Prussia, residing at Cologne, in the Empire of Germany, have invented a new and useful Improvement in Igniting Apparatus for Gas and Oil Motor Engines, (for which I have obtained a patent in Italy, dated December 17, 1889, Vol. LII, No. 180, and in Great Britain by an application for patent, which patent, when granted, will bear date November 22, 1889, No. 18,746,) of which the following is a specification.

This invention relates to the construction of igniting apparatus for gas and oil motor engines, consisting of metal tube heated by an external flame and surrounded by a casing such as was described in the specification to Patent No. 386,929, of July 31, 1888.

According to the present improvement, instead of effecting the heating of the metal tube by a gas-flame, it is heated by a flame of petroleum-vapor. For this purpose the apparatus is constructed as shown on the accompanying drawings, in which—

Figure 1 shows a longitudinal section of the apparatus; and Fig. 2, a cross-section on line X X, Fig. 1.

The heated igniting-tube *h*, which ignites the cylinder charge when its interior is put in communication therewith in the known manner, is fixed in the passage of casing *b*, leading to the engine-cylinder *C*. At a point by preference as near the cylinder as possible a passage *b'* is formed extending partially round it, and between the two open ends of the passage an opening is formed on the under side of the casing surrounded by a branch tube *f*. To the one end of the passage *b'* is attached a pipe *a*, communicating with a supply of liquid petroleum, and to the other end is attached a pipe *d*, terminating in a nozzle facing the branch tube *f*, in which is fixed a transverse metal rod *g*.

Assuming the casing *b* to be in a heated condition, the liquid petroleum entering the passage *b'* of the casing from pipe *a* will become volatilized by the heat, and the vapor

issuing with force from the nozzle of *d* will carry the requisite air-supply along with it through the branch tube *f*, and in entering 50 into combustion the resulting flame produced in the space *c* will impinge upon the igniting-tube *h* and the interior of the casing *b*, thereby highly heating these parts and the passage *b'*, in which the liquid petroleum is vaporized. 55 The intimate mixture of the jet of petroleum-vapor with the air carried by it is insured by causing the jet of vapor to impinge upon the rod *g*, whereby it is effectually opened out.

For heating the igniting-tube and casing 60 in the first instance on starting the engine an oil spirit-lamp is temporarily placed under the branch tube *f*.

By arranging the passage *b'* and jet *d* as close as possible to the cylinder the heat is 65 concentrated at that point and acts in the most advantageous manner in firing the charges.

Having thus described the nature of my invention and the best means I know for carrying the same into practical effect, I claim—

In apparatus for igniting the charges of gas or oil motor engines, the combination, with the igniting-tube *h*, of a tubular casing *b*, having a channel *b'*, into which liquid petroleum is introduced through a pipe *a*, a branch tube *f*, with metal rod *g*, and a pipe *d*, with nozzle through which petroleum-vapor formed in the passage *b'* issues into the branch tube *f*, and in mixing with the necessary air enters into combustion within the casing, so as to heat this and the tube *h* at a point near the engine-cylinder, substantially as described.

In testimony whereof I have signed my 85 name to this specification, in the presence of two subscribing witnesses, this 4th day of December, A. D. 1889.

NICOLAUS AUGUST OTTO.
